UNITED STATES PATENT OFFICE

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN

GUN

Application filed October 14, 1929. Serial No. 399,634.

The invention relates to air guns and has for its object the simplifying of the construction and the obtaining of various advantages. To this end the invention consists in various 5 features of construction as hereinafter set forth.

In the drawings:

Figure 1 is a side elevation of my improved gun; 10 Figure 2 is a vertical central longitudinal section through the frame portion of the gun with the parts in normal position;

Figure 3 is a similar view showing the handle drawn rearward to compress the spring 15 and to engage the plunger shank with the sear;

Figure 4 is a similar view showing the handle moved forward but not quite to its normal position and also showing the trigger locking mechanism which remains effecting 20 in this position of the handle;

Figures 5, 6 and 7 are cross sections respectively on lines 5—5, 6—6 and 7—7 of Figures 2 and 3;

Figure 8 is a perspective view of the trigger locking lever;

Figure 9 is a perspective view of the end of the plunger shank which is engaged by the shank of the pump handle and the sear;

Figure 10 is a perspective view of the air compressing plunger and its shank detached;

Figure 11 is a longitudinal section showing these members in engagement with each other;

Figure 12 is a plan view of the sheet metal blank from which the shank of the pump handle is formed;

Figure 13 is a perspective view of a portion of this shank formed up from the blank;

Figure 14 is a sectional perspective view 40 showing the manner of securing the guide for the handle;

Figure 15 is a vertical longitudinal section through the muzzle portion of the gun showing the manner of engaging the removable 45

shooting and magazine barrel unit therewith;

Figure 16 is a perspective view of the shooting and magazine barrel unit removed from the barrel;

Figure 17 is a cross section on line 17—17 of 50 Figure 15 showing the manner of locking the shooting barrel in the gun.

Figure 18 is a perspective view of the plunger spring and abutment unit removed.

My improved gun is of the type known as 55 pump gun where the compression of the spring is accomplished by the movement of a handle parallel to the barrel of the gun.

Usually with such constructions there is interposed between the handle and the spring 60 compressing plunger a lever mechanism or some equivalent means for increasing the power exerted upon the spring. Such mechanism necessarily complicates the construction and increases the cost of manufacture 65

but has heretofore been deemed necessary in order to avoid too great labor on the part of the operator in compressing the spring. With the present invention I have dispensed 70 with this intervening lever mechanism and actuate the plunger by the direct push of the handle. I have also lessened the labor of compression by substituting for the usual heavy gauge spring a relatively light spring.

With the present invention I have dispensed 75 with this intervening lever mechanism and actuate the plunger by the direct push of the handle. I have also lessened the labor of compression by substituting for the usual heavy gauge spring a relatively light spring.

I have reduced the frictional resistance to the movement of the plunger so that substantially the same degree of air compression is attained.

In detail, A is the false barrel or muzzle 80 of the gun which is preferably formed integral with the frame portion B both being struck up from a single sheet metal blank. A portion C of the false barrel forms the air compression cylinder at the forward end of which is the piston abutment D. E is the plunger for engaging the barrel C, F the plunger shank, G the spring and H a spring abutment.

As has been stated the spring G is relative- 90

ly light and is arranged to have one end engage the abutment H and the opposite end the plunger E. This plunger is so constructed as to reduce frictional resistance and to 5 this end is provided with a head E' smaller than the diameter of the air compression cylinder and a cup packing E² formed of leather or other soft material. This cup packing is secured to the head E' by a washer E³ which 10 has a press fit upon an integral shank E⁴ of the head E'. Preferably the washer E³ is originally of dish shape and apertures to fit over the shank E⁴ which shank has a flaring portion E⁵ adjacent to the head E'. Thus 15 when the cup washer is forced on to the shank and over the flaring portion with sufficient pressure to straighten out the cup this will develop sufficient radial pressure to retain the washer in position and to clamp the cup E² 20 to the head E'. The head E' is further provided with the usual air tube E⁶ which projects forward through the apertured abutment D and has the port E' for the passage of the compressed air therethrough from the 25 cylinder.

The plunger shank F is formed from a sheet metal blank which is fashioned into a forward cylindrical or tubular portion F' adapted to fit over the shank E⁴ of the head 30 E' and to be secured thereto by a cross pin F². In rear of this cylindrical portion is a bifurcated portion F³ which terminates in an inverted U-shaped portion F⁴. Between the parallel sides of the portion F⁴ is inserted an 35 inverted U-shaped member F⁵ which has downwardly projecting spaced prongs F⁶ and F⁷ which pass through apertures in the portion F⁴ and are riveted for retention therein.

The plunger shank F passes through an 40 aperture in the spring abutment H with the downturned prongs F⁶ and F⁷ arranged in rear of said abutment. To permit of this the spring abutment H is assembled with the plunger and its shank outside the false barrel A and the assembled unit is then inserted 45 in the barrel and frame. This spring abutment is also formed from a sheet metal blank which is formed into a cylindrical fitting and telescopically engaging the false barrel and 50 frame of the gun. The rear portion of this cylinder is slotted at H' on its under side to form guides for the downward projecting prongs F⁶ and F⁷ of the plunger shank. Forward of this slotted portion the member H is 55 provided with a bushing H² welded or otherwise rigidly secured thereto which bushing forms the direct abutment to the end of the spring. The rear end of the member H is notched at H³ to engage the trigger pivot I 60 which latter also forms the anchor for the abutment and receives the thrust of the spring.

With the parts as thus far described, in assembling the same the plunger shank F is 65 inserted from the rear through the bushing

H² with the prongs F⁶ and F⁷ entering the slots H'. The spring G is then sleeved upon the shank F after which the head E' is secured to said shank by means of the pin F². This forms an assembly which can be inserted 70 from the rear through the frame of the gun and into the false barrel thereof until the plunger E bears against the plunger abutment D. The pin I is then inserted to engage the notch H³ which will anchor the assembly 75 in the frame.

The pump handle J is of cylindrical form grooved on its upper face to fit against a segment of the false barrel and to slide thereon. K is the shank of the handle which is formed up from a sheet metal blank in a U-shaped cross section K' provided at its forward end with a cylindrical portion K² which extends through a central bore in the handle J. Between the cylinder portion and the H-shaped portion there is formed a shoulder K³ abutting against the end of the handle and ears K⁴ at the forward end of the cylinder portion and turned over on the handle to lock the shank thereto. At its rear end the shank is 90 provided with a laterally extending lug K⁵ which is adapted to engage the prong F⁶ of the plunger shank so that when the handle is drawn rearward it will carry with it the plunger shank F, plunger E and compress the 95 spring G. To guide the handle in this movement the shank K passes through an aperture in the forward end of the frame B while at its forward end the handle is guided on a guide bar L. The latter is inserted through 100 a loop bracket L' attached to the under side of the barrel A and the bar L is then slid forward through the tubular portion K² and into the U-shaped portion on the shank. The bar L is secured by a pin L² fastening the same to the bracket L' and the arrangement is such that this bracket holds the bar parallel 105 to the barrel so as to form a guide for the movement of the handle.

The trigger M and sear N are formed up 110 from sheet metal into substantially U-shaped cross sections, the sear being embraced by the trigger and both members being apertured to engage the pivot pin I. The sear is yieldably pressed upward in a position where a notch N' therein will engage the prong F⁷ of the plunger shank when the latter is moved rearward. This yielding pressure is supplied by a spring N² which engages a lug N³ on the sear and at its opposite end engages a lug on 115 a lever O which is pivoted within the frame of the gun. This lever O forms a trigger lock which prevents any movement of the trigger to disengage the sear during movement of the handle J in compressing the 120 spring, the construction being as follows:

At the forward end of the lever O there is a 125 notch O' which normally engages the laterally projecting lug K⁵ on the handle shank K. When thus engaged the lever O is rocked into 130

a position where its rear end is slightly raised against the tension of the spring N^2 . O^2 is a laterally projecting lug at the rear end of the lever O which in the position of said lever just described will clear a rearwardly projecting lug M' on the trigger M . However, whenever the lug K^5 on the shank K is withdrawn from the notch O' the lever O will be rocked by the tension of the spring N^2 so that the lug O^2 extends in rear of the lug M' thereby locking the trigger from being drawn backward. This position of the lever O will be maintained during the entire operation of drawing the handle J rearward and moving it forward again up to the position shown in Figure 4 where the handle is nearly to its forward position. The final forward movement of the handle will cause the lug K^5 to ride over a cam O^3 on the lever O thereby depressing the forward end of said lever and raising the lug O^2 out of engagement with the lug M' or into the position shown in Figure 2. In this position the lug K^5 again engages the notch O' which will hold the handle J from accidental movement on the guide rod L .

The shooting barrel is detachably engageable with the false barrel A and is combined with a magazine, the construction being as follows:

The barrel P which is formed of straight tubing has its rear end fitting within the piston abutment D . Surrounding this barrel is a member Q formed from sheet metal having a segmental portion Q' fitting about the barrel P and upwardly extending parallel flanges Q^2 for forming a magazine. The rear end of the member Q has secured thereto the collar Q^3 which bears against the forward face of the piston abutment. Adjacent to and forward of this collar the barrel P is apertured for the passage of shot from the magazine thereinto. At the forward end of the member Q there is attached a cam member R which telescopically engages the false barrel A and holds the barrel P in axial alignment therewith. The member Q has a lug Q^4 laterally projecting from one side thereof and in a position to catch behind the segmental shank S of the sight S' . This segment is welded or otherwise secured within the barrel and forms a shoulder which when engaged by the member Q^4 will hold the barrel P in a position with the collar Q^3 bearing against the piston abutment. Thus to engage the barrel and magazine with the false barrel the unit is first turned a partial revolution from its normal position and is inserted in the false barrel. By then rotating it to the normal position the member Q^4 will be engaged with the member S and the magazine formed by the flanges Q^2 will be arranged on the upper side of the barrel P . To load the magazine, the cap R is turned a slight distance so as to register a port T in the barrel A with the magazine, thereby per-

mitting the insertion of the shot. The cap is then turned in the reverse direction to its normal position which closes the aperture T .

In operation, to load the gun the handle J is drawn rearward upon the guide L which causes the lug K^5 on the shank K to engage with the prong F^6 of the piston shank F carrying this shank rearward and thereby compressing the spring G . At the completion of the rearward movement the prong F^7 will engage with the notch N' of the sear N thereby holding the spring in compressed position during the movement of the handle forward to its normal position. The trigger M is locked upon the initial movement of the handle J rearward by the rocking of the lever O and the arrangement of the lug O^2 in rear of the lock M' . This position is maintained in all positions of the handle until it again resumes its original forward position which, as previously described, unlocks the trigger by tilting the lever O . The gun may then be fired by pulling upon the trigger M which rocks the sear N downward disengaging the notch N' from the prong F^7 .

It will be noted that the handle J is arranged in close proximity to the barrel A and moves parallel to the axis of said barrel. Also, that the only point of bearing for the piston or plunger is the cup shaped packing E^2 . This will reduce friction so that with the light spring G the user may easily draw the handle backward to compress the spring. When the gun is fired the cup E^2 is still the only member frictionally contacting the barrel or any stationary part so that the full force of the spring is exerted to compress the air. Thus I have accomplished with a greatly simplified mechanism functions which usually require a more complex structure.

One of the advantageous features of my improved construction is that the plunger, the spring and the spring abutment can be assembled in relation to each other to form a unit which is insertable within or detachable from the barrel or frame. Obviously it is much easier to assemble these parts outside of the barrel than in it and furthermore, units of this kind can be assembled in advance of the assembling of the other parts of the gun so as to be available for use at any time. To insert the unit in the gun it is only necessary to insert it from the rear end of the frame, moving it forward until the abutment H engages the barrel A and the plunger E engages the abutment D . Then when the trigger and sear are placed in position the pivot pin therefor is inserted which locks the member H from rearward movement.

What I claim as my invention is:

1. In a gun, the combination with a false barrel and a frame integral therewith, said false barrel having an air compression cylinder formed therein with a piston abutment

at the forward end of said cylinder, of a plunger spring and abutment unit insertable into said frame and false barrel from the rear end thereof, a trigger, a sear and a pivot for said trigger and sear extending through said frame and forming an anchor for said spring abutment.

2. In a gun, the combination with a false barrel and an inverted U-shaped frame formed integral therewith, said false barrel having an air compression cylinder formed in a portion thereof with a piston abutment at the forward end, of a plunger spring and abutment unit comprising a cylindrical abutment member having its forward end adapted to telescopically engage the false barrel with its rear portion engaging said frame and slotted on its under side, a plunger shank extending through said cylindrical abutment having a downwardly extending portion engaging said longitudinal slot, a spring sleeved upon said shank between said plunger and said abutment, said unit being insertable through the rear end of said frame, a trigger, a sear and a pivot for said trigger and sear passing through said frame and also constituting an anchor for said abutment.

3. In an air gun, the combination with an air cylinder, of a plunger therefor comprising a headed member having a tapered shank, a cup shaped packing sleeved upon said shank and bearing against said headed member and a washer pressed on said tapered shank to be fixed thereon, said washer bearing against said cupped packing and retaining the same upon said headed member.

4. In an air gun, the combination with an air cylinder, of a plunger therefor comprising a headed member having a short shank with a tapered portion adjacent to the head, a cupped washer sleeved upon said shank with its cupped flange overlapping said head, a washer pressed upon said shank to be fixed upon the tapered portion thereof and to retain said packing in position and a tubular shank engaging said short shank and extending rearward therefrom.

5. In an air gun, the combination with an air cylinder, of a plunger therefor comprising a headed member with a short shank, a cupped washer sleeve upon said shank with the cup flange overlapping the headed portion, a washer pressed upon said shank to retain said cupped packing thereon, a shank formed from a sheet metal blank having a cylindrical forward portion for engaging said short shank and being coupled therewith, the rear end of said sheet metal shank having a portion of inverted U-shaped cross section and an inverted U-shaped member arranged in the longitudinal plane of said shank and embraced by the U-shaped portion thereof, said last mentioned U-shaped member being provided with laterally extending lugs engaging apertures in the opposite sides

of the shank and riveted for retention therein.

6. In a gun, the combination with a frame and a false barrel having an air cylinder formed therein, a plunger in said cylinder, a spring and a spring abutment, of a handle slidable upon said barrel, a hollow shank extending rearward from said handle and into said frame to engage said plunger, a guide bar for said handle extending axially therethrough and into said hollow shank and a bracket on said false barrel provided with a loop bearing for engaging said guide bar whereby the latter may be inserted therethrough endwise to engage said handle and hollow shank.

7. In a gun, the combination with a frame, a false barrel having an air cylinder therein, a plunger in said cylinder, a plunger shank, a spring sleeved upon said plunger shank, a spring abutment for said spring, a handle slidable upon said barrel, a handle shank extending into said frame into engagement with said plunger shank to actuate the same rearwardly, a lug depending from said plunger shank for engaging said handle shank, a trigger and a sear pivotally mounted in said frame, a lever pivoted in said frame adapted in one position to engage said trigger so as to lock the same from movement, a lug on said handle shank for engaging said lever to adjust the same into a position for releasing said trigger, said lug being withdrawn from said lever during the movement of said handle to retract said plunger and to compress said spring whereby said trigger will be locked until the return of said handle.

8. In a gun, the combination with a false barrel and a frame, a plunger within said false barrel, a plunger shank, a spring for said plunger, a handle slidable on said false barrel, a handle shank extending into said frame to engage said plunger shank and to actuate the same in the direction to compress said spring, said handle shank being formed of a sheet metal blank fashioned into a U-shaped cross section and provided at its inner end with a laterally extending lug for engagement with said plunger shank, a guide for said handle extending axially through the same and into said U-shaped shank, and a bracket on said false barrel having a loop bearing for said guide permitting of inserting the same therethrough into engagement with said handle and to then guide said handle in its movement.

9. In an air gun, the combination with a false barrel having a piston abutment therein, of a combined shooting barrel and magazine unit insertable in said false barrel, said unit comprising a tube for forming the shooting barrel with a rear portion thereof engaging an aperture in said piston abutment, a sheet metal member provided with a segmental portion telescopically engaging with said

tube and secured thereto, said member being also provided with parallel spaced flanges to form a trough for receiving the projectiles, a collar upon said sheet metal member adapted to engage said piston abutment, a cap at the opposite end of said sheet metal member for engaging the muzzle end of said false barrel and means for locking said cap from disengagement from said false barrel on a partial rotation thereof.

In testimony whereof I affix my signature.
CHARLES F. LEFEVER.
